UNITED STATES PATENT OFFICE.

MICHAEL F. BROGAN, OF LAWRENCE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WELT-BEATING MACHINE.

1,306,656.

Specification of Letters Patent. Patented June 10, 1919.

Application filed July 28, 1917. Serial No. 183,353.

To all whom it may concern:

Be it known that I, MICHAEL F. BROGAN, a citizen of the United States, residing at Lawrence, in the county of Essex and State of Massachusetts, have invented certain new and useful Improvements in Welt-Beating Machines; and I do hereby declare the following to be a full, clear, and exact description of the invention, such as will enable others skilled in the art to which it appertains to make and use the same.

This invention relates to welt beating machines for beating out the welt of a lasted shoe, and more particularly to welt beating machines of the class provided with welt slashing mechanism for cutting slashes in the welt to enable it more readily to be beaten out flat in the plane of the insole of the shoe.

The objects of the present invention are to improve the construction, operation and efficiency of welt beating machines of the above class, and to provide such machines with a welt slashing mechanism having a simplified construction and an improved mode of operation as compared with prior machines.

In this class of machines the welt slashing mechanism is normally out of operation, and is arranged to be thrown into and out of operation during the continued operation of the machine by mechanism under control of the operator, such as a treadle. The welt slashing mechanism is ordinarily thrown into operation only when operating about the toe of the shoe where the welt is warped or thickened by reason of the strain exerted upon its outer margin in attaching the same about the convex curve of the toe. It is practically always necessary to make several slashes in the welt about the toe to enable the welt to be beaten out properly. In prior machines the welt slashing mechanism is thrown into operation by the depression of a treadle, and is thrown out of operation immediately upon release of the treadle. In these machines in making the number of slashes required in the welt about the toe of a shoe to enable the welt to be beaten out properly it is necessary for the operator to keep his foot on the treadle until the required number of slashes are made, and then to release the treadle.

One feature of the present invention contemplates the provision of mechanism oper-

ating automatically after the welt slashing mechanism has been thrown into operation to cause the welt slashing mechanism to cut at least a predetermined number of slashes in the welt before it is thrown out of operation. The above feature is of great advantage, since it enables the required number of slashes to be made in the welt without further attention on the part of the operator after the treadle is actuated to throw the welt slashing mechanism into operation, and insures the making of at least the number of slashes required for satisfactory results without the exercise of any care or judgment by the operator.

In the usual machines of this class now in commercial use the welt slashing knife is constructed and arranged to move during its cutting stroke in a straight line in the plane of the welt from the outer toward the inner edge of the welt. With this construction and arrangement of the knife the operating movement of the knife tends to crowd the outer margin of the welt inwardly toward the shoe and the result often is that the knife does not make a clean cut of the desired length in the welt. This is particularly true when the knife becomes slightly dulled.

Other features of the present invention relate to improvements in the construction, arrangement and mode of operation of the welt slashing knife. Certain of these features will obviate the above disadvantage in the mode of operation of the knife in prior machines of the usual type.

The invention also comprises certain other novel and improved constructions, arrangements and combinations of parts hereinafter described and particularly pointed out in the claims, the advantages of which will be readily appreciated by those skilled in the art.

The features of the invention will be readily understood from the accompanying drawings illustrating the invention in its preferred form, and the following detailed description of the constructions therein shown: In the drawings, Figure 1 is a perspective view of a machine embodying the invention, with certain of the parts broken away; Fig. 2 is a view in side elevation of a portion of the machine illustrating particularly the beating hammer and slashing knife mechanisms; Fig. 3 is a view similar to Fig. 2,

illustrating certain of the parts of the knife mechanism in different positions, with certain of the parts shown in section; Fig. 4 is a detail sectional view taken substantially on the line 4—4 of Fig. 2; Fig. 5 is a plan view of the forward portion of the machine below the hammer lever, and illustrating particularly the slashing knife mechanism; Fig. 6 is a detail view in front elevation, with certain parts in section illustrating the knife mechanism; Fig. 7 is a view similar to Fig. 6, illustrating certain of the parts in different positions; and Fig. 8 is a detail sectional view taken substantially on the line 8—8 of Fig. 5.

The general organization of the machine illustrated in the drawings, and the construction and arrangement of the parts of the welt beating mechanism are substantially the same as in the machine illustrated and described in the patent to Hadaway No. 875,171, dated December 31, 1907. The machine comprises a welt support 2, shaped at its forward end to enter between the upper and welt of a lasted shoe, and a vibratory hammer 4 arranged to engage and beat out the welt as it is fed across the upper surface of the welt support. The welt support is adjustably secured to a forwardly projecting arm 6 on the frame of the machine. The hammer 4 is secured to the lower end of a hammer rod or plunger 8 slidably mounted in guides in the forward end of a hammer lever 10, and acted upon by a coiled spring (not shown) surrounding the rod within a chamber in the hammer lever and acting to hold the rod yieldingly in its lower limiting position in the hammer lever, and allowing the hammer to yield when it engages the welt. The hammer lever is fixed to a shaft 12 mounted in suitable bearings in the frame of the machine. The hammer lever is rapidly oscillated by means of an eccentric or crank 14 formed on the main shaft of the machine and operating within a two-part bearing block 18 mounted in guides in the bifurcated rear end of the hammer lever. The main shaft is mounted in suitable bearings in the frame of the machine and carries a driving pulley 20. The construction thus far described is substantially the same as that of the machine illustrated and described in the Hadaway patent referred to above.

The welt slashing knife of the machine is indicated at 22. The knife is formed upon the forward end of a knife bar 23 clamped in a carrier 24 pivoted by means of a shaft 26 upon a support 28. The rear end of the knife bar is dovetailed in cross-section, and fits in a corresponding dove-tailed slot formed in the carrier 24. The knife bar is clamped in the carrier by means of a clamping block 30 fitting in a slot in the carrier 24 and arranged to engage the edge of the

knife bar and a clamping screw 32 passing through an opening in the carrier and threaded at its end into the clamping block 30. The knife is formed with a curved cutting edge extending in a direction from one edge of the knife bar toward the other and from the outer side of the knife bar toward the inner side thereof. The knife bar is mounted in the carrier 24 so that the knife formed at the forward end thereof projects over the upper surface of the welt support in position to engage the welt as the welt is fed across the upper surface of the welt support. To impart a cutting stroke to the knife, the carrier 24 is swung from the position shown in Fig. 6 to that shown in Fig. 7. As illustrated in the drawing, the pivot of the carrier 24 is substantially perpendicular to a vertical plane through the line of feed. As the knife is swung from the position shown in Fig. 6 to that shown in Fig. 7, it will engage the welt and cut a slash therein extending obliquely to the plane of the welt partially through the welt from its upper or flesh side toward its lower or grain side. During its cutting stroke the knife moves in a direction transverse to the plane of the welt and in the general direction of the length of the welt and has no movement in a direction widthwise of the welt. The knife therefore will have no tendency to crowd the outer portion of the welt inwardly toward the shoe, but will make a clean slash of the desired length in the welt. The slashes made by the knife will therefore extend substantially uniform distances from the outer toward the inner edge of the welt, and will terminate at substantially uniform distances from the lower face of the welt which rests upon the welt support.

To enable the knife to be adjusted angularly in a plane substantially parallel with the plane of the welt, the support 28 is mounted upon a slide 34 having a cylindrical boss 36 projecting upwardly therefrom and engaging in a corresponding cylindrical recess in the support 28, as shown clearly in Figs. 3 and 5. This manner of mounting the support 28 on the slide 34 allows the support to be swung about the center of the boss 36 as an axis. The support 28 is held in adjusted position on the slide 34 by means of holding screws 40 and 41 passing through slots in the support 28 and threaded into the slide 34. By the adjustment of the knife angularly in a plane substantially parallel with the plane of the welt, the angular positions of the slashes made in the welt relative to the length of the welt may be varied. The slide 34 is dove-tailed in cross-section, and is mounted in guides in a support 42 to slide in a direction substantially parallel with the line of feed. This manner of mounting the slide 34 on the support 42 enables the knife to be adjusted lat-

erally to locate the knife properly relatively to the welt support and the welt beating hammer. The slide 34 may be adjusted laterally relatively to the support 42 by means 5 of an adjusting nut 44 threaded upon a bolt or stud 46 secured at one end in the support 42, the nut being formed with a peripheral groove in which engages a downwardly extending arm 48 on the slide 34. The knife 10 also may be adjusted angularly in a plane substantially perpendicular to the plane of the welt to vary the angle of the slashes relatively to the plane of the welt. To enable the knife to be adjusted in this plane, the 15 support 42 is formed with a substantially semi-cylindrical bearing boss or projection 50 which fits into a correspondingly shaped recess in the shank of the welt support 2. This construction enables the support 42 to 20 be tipped about the axis of the cylindrical boss 50. The support 42 may be adjusted about the axis of the bearing boss 50, by means of an adjusting screw 52 threaded into the support 42 and engaging the shank 25 of the welt support at its lower end, as shown in Fig. 3. The support 42 is securely held in position in the machine my means of an eye-bolt 54 pivoted upon a stud 56 mounted in the support 42 and extending 30 downwardly through a slot in the shank of the welt support and through the arm 6 on the frame, and a nut 57 threaded upon the lower end of the bolt and engaging a washer 58 interposed between the nut and the arm 35 6. The eye-bolt and nut serve not only to secure the support 42 in place, but also to hold the welt support in adjusted position upon the arm 6.

In the present machine the carrier 24 is 40 swung from the position shown in Fig. 6 to that shown in Fig. 7 to impart a cutting stroke to the knife from the movement of the hammer lever. The knife is normally held in retracted or inoperative position by 45 means of a plunger 59 mounted in a suitable guide in the support 28, and arranged to engage the carrier 24, as shown in Figs. 6 and 7. The plunger is acted upon by a coiled spring 60 surrounding the rod which 50 forms the shank of the plunger, and interposed between the head of the plunger and a cap 62 threaded on the end of a projection or boss 64 formed on the support 28. The plunger 58 is normally held by the coiled 55 spring 60 in advanced position in its guide bore in the support 28 and normally maintains the carrier 24 in the position shown in Fig. 6. The movement of the carrier 24 under the action of the plunger is limited 60 by the engagement of an abutment 66 formed on the carrier with the abutment face 68 on the support 28. The carrier 24 is swung from the position shown in Fig. 6 to that shown in Fig. 7, to impart a cutting 65 stroke to the welt slashing knife by means

of a lever 70 pivoted upon a stud 72 projecting from a bracket 73 secured to the hammer lever. The lever 70 is arranged to engage at its forward end a contact plate 74 secured by a screw 76 to a projection 78 on the carrier 24. The rear end of the lever 70 is acted upon by a compression spring 80 interposed between the bracket 73 and the rear end of the lever 70 which normally maintains the forward end of the lever 70 75 in its uppermost position in engagement with a projection on the bracket 73, as shown in Fig. 2. When the lever 70 is held in the position shown in Fig. 2, the forward end of the lever does not engage the contact 80 plate 74 during the downward movement of the forward end of the hammer lever. To throw the knife into operation, an abutment 84 is positioned so as to engage the under side of the rear end of the lever 70 85 during the downward movement of the forward end of the hammer lever, to cause the forward end of the lever 70 to swing downwardly relatively to the hammer lever into engagement with the contact plate 74, and 90 swing the carrier 24 from the position shown in Fig. 6 to that shown in Fig. 7. The abutment 84 consists of a slide mounted to slide vertically in suitable guides in an upright 86 on the frame. The downward 95 movement of the abutment 84 is limited by an offset or lateral projection 88 at the upper end thereof, which is arranged to engage the upper end of the upright 86. The abutment is illustrated in its lowermost 100 position in Fig. 2. When the abutment is lifted from the position illustrated in Fig. 2 to that illustrated in Fig. 3, its upper end engages the rear end of the lever 70 during the downward movement of the forward end 105 of the hammer lever, and causes the lever 70 to swing about the shaft 72 relatively to the hammer lever from the position shown in Fig. 2 into the position shown in Fig. 3. During this movement of the lever 70 relatively to the hammer lever the carrier 24 is 110 swung about its pivot 26 to impart a slashing stroke to the welt slashing knife.

The abutment 84 is lifted from the position shown in Fig. 2 to that shown in Fig. 115 3 by means of a cam wheel 90 secured to a shaft 92 mounted in bearings formed respectively in a plate 94 secured to the frame of the machine, and in the upright 86. The cam wheel 90 is arranged to be rotated in 120 the direction indicated by the arrow in Fig. 3, and is formed with a plurality of arms or projections 96 having forwardly directed cam faces for engaging the lower end of the abutment 84 and lifting the same from the 125 position shown in Fig. 2 to that shown in Fig. 3. In the illustrated construction the cam wheel is formed with four arms, although this number may be varied as found to be desirable. The cam wheel is normally 130

held stationary substantially in the position shown in Fig. 2, with the lower end of the abutment 84 located between two of these projections 96. The cam wheel is held in this position by means of a roll 98 mounted on the upper end of a slide 100, and arranged to engage in a recess 102 in a disk 104 fixed to the shaft 92 to hold the disk and the shaft from rotation. The slide 100 is mounted to slide vertically in suitable guides on the frame of the machine, and is normally held in its upper position with the roll 98 engaged in the recess 102 by means of a compression spring 106 mounted in a slot 108 in the slide and interposed between the upper end of the slot and a pin 110 mounted on the frame. The lower end of the slide 100 is connected with the upper end of a treadle rod 112 by means of which the slide may be depressed to disengage the roll 98 from the recess 102 to permit the rotation of the cam wheel 90. The disk 104 is formed with a substantially circular periphery, except at the point where the recess 102 is located.

Mechanism is provided for rotating the cam wheel 90 which is held out of operation as long as the slide 100 is in its upper position and is thrown into operation by the depression of the slide.

The mechanism for rotating the cam wheel 90 comprises a ratchet wheel 114 fixed to the shaft 92, and a pawl 116 mounted on a pawl carrier 118 loosely pivoted on the shaft 92. The pawl 116 is pivoted upon a shaft 120 mounted in the pawl carrier 118, and is acted upon by a compression spring 122 interposed between an arm 124 on the rear end of the pawl and the pawl carrier, which tends to throw the forward end of the pawl into engagement with the ratchet wheel 114. The pawl carrier 118 is oscillated continuously during the operation of the machine by mechanism comprising an arm 126 secured at its rear end to the hammer lever shaft 12, and provided at its forward end with a slot 128 through which the shaft 92 passes. The arm 126 is connected with the pawl carrier 118 by means of a block 130 pivoted on a pin 132 secured in the pawl carrier, and arranged between suitable guides formed by the opposite faces of a slot in the arm 126, as shown clearly in Fig. 8. Oscillating movements are imparted to the arm 126 by the rocking movement of the shaft 12 caused by the oscillation of the hammer lever 10. The oscillation of the arm 126 through the connection between said arm and the pawl carrier 118 will impart oscillating movements to the pawl carrier. When the acting end of the pawl 116 is engaged with the ratchet wheel 114, the ratchet wheel will be rotated step by step by the action of the pawl. The parts are preferably constructed and arranged so that

the ratchet wheel will be advanced one tooth during each oscillation of the pawl carrier. Backward movement of a ratchet wheel is prevented during the retraction of the pawl by means of a retaining pawl 134 pivoted upon a stud 136 mounted on the plate 94, the pawl being formed with a hook-shaped end arranged to engage the teeth on the ratchet wheel. The acting end of the retaining pawl is held in engagement with the teeth on the ratchet wheel by means of a tension spring 138 attached at one end to an arm 140 on the pawl, and at its other to the plate 94.

The pawl 116 is normally held out of engagement with the ratchet wheel 114 so that the pawl oscillates idly. To this end the rear end of the pawl carries a roll 142 arranged to be engaged by a curved contact face 144 formed on the slide 100. The contact face 144 is preferably struck upon an arc having its center substantially in the axis of the shaft 92. The parts are constructed and arranged so that when the slide 100 is in its uppermost position with the roll 98 engaged in the recess 102, the roll 142 on the pawl 116 will be engaged by the contact face 144 on the slide, and the pawl will be held out of engagement with the ratchet wheel 114.

During the normal operation of the machine, the treadle of the machine is released, and the slide 100 is in its uppermost position with the roll 98 engaged in the recess 102 in the disk 104, thereby holding the disk, the shaft 92, and the cam wheel 90, stationary in a position such that the abutment 84 is in its lowermost position between two of the projections 96 on the cam wheel, and the pawl 116 is held out of engagement with the ratchet wheel 114 by the engagement of the contact face 144 on the slide 100 with the roll 142. The welt slashing mechanism is thus held out of operation as long as the treadle is released. In the operation of beating out the welt of a shoe as the point is reached in the shoe, such as the toe, at which it is desirable to cut a number of slashes in the welt, the operator depresses the treadle rod 112. The slide 100 is thus depressed to disengage the roll 98 from the recess 102 and to carry the contact face 144 on the slide out of engagement with the roll 142 on the pawl 116, allowing the pawl to be actuated by the spring 122 to carry the acting end of the pawl into engagement with the ratchet wheel 114. The ratchet wheel is then rotated step by step by the oscillatory movements of the pawl 116. By the actuation of the ratchet wheel the cam wheel 90 is rotated in the direction of the arrow, Fig. 3, carrying the projections 96 on said wheel successively into engagement with the lower end of the abutment 84 to lift said abutment 130.

at intervals into the position shown in Fig. 3, so that it will engage the rear end of the lever 70 and cause said lever to actuate the carrier 24 to advance the welt slashing 5 knife. The welt slashing knife will be actuated to cut one slash in the welt each time that the abutment 84 is lifted into its operating position. The initial rotary movement of the ratchet wheel 114 rotates the 10 disk 104 to carry the recess 102 in the disk out of position to be entered by the roll 98. After depressing the treadle to throw the welt slashing mechanism into operation, the operator releases the treadle, allowing 15 the slide 100 to be elevated by the action of the spring 106, thereby carrying the roll 98 into engagement with the circular periphery of the disk 104. The parts are constructed and arranged so that when the roll 20 98 is engaged with the circular periphery of the disk 104, the slide 100 will be held down far enough to prevent the engagement of the contact face 144 on the slide with the roll 142. The pawl 116 will therefore 25 continue to engage the ratchet wheel 114 until the disk 104, the shaft 92 and the cam wheel 90 have made a complete rotation. As these parts complete a full rotation bringing the recess 102 to its initial position the 30 slide 100 is elevated by the spring 106 thereby engaging the roll 98 in the recess and the pawl 116 is thrown out of engagement with the ratchet wheel 114 by the engagement of the contact face 144 in the 35 slide with the roll 142. Therefore, after the treadle is depressed to throw the welt slashing mechanism into operation, and is then released, the cam wheel 90 will make a complete rotation before it again comes 40 to rest. After the welt slashing mechanism is thrown into operation by the operator, the welt slashing knife will be actuated to make at least a predetermined number of slashes at regular intervals in 45 the welt and said mechanism is then thrown out of operation automatically. The number of slashes made in the welt during the period of operation of the welt slashing mechanism is determined by the number of 50 projections on the cam wheel 90, which obviously may be varied as desired. In the illustrated construction the cam wheel is formed with four projections and the welt slashing knife will be actuated to cut four 55 slashes in the welt. This is usually the maximum number required to be made at the toe of a shoe in order to enable the welt to be beaten out in a reliable and satisfactory manner. The ratchet wheel 114 60 is advanced one tooth during each oscillation of the welt beating hammer. In the illustrated construction, the ratchet wheel is formed with twelve teeth, so that during the period of operation of the slashing 65 mechanism the welt slashing knife makes one slash in the welt for each three blows delivered by the hammer on the welt. The intervals between the slashing strokes of the knife or the number of blows delivered by the hammer on the welt for each stroke 70 of the knife may be varied by varying the number of teeth on the ratchet wheel. 75 The hammer illustrated in the drawings is a two-part hammer having substantially the same construction and arrangement of parts as the hammer illustrated and described in the patent to Seely & Hadaway, No. 1,196,486, dated August 29, 1916. 80 In the illustrated construction the hammer comprises two beaters indicated, respectively, at 146 and 148. The beater 146 is provided with a sleeved shank which receives and is secured to the lower end of the hammer rod 8. The beater 148 is provided with a pivot stud 150 which is engaged in a 85 bearing in a projection 152 on the beater 146, a nut 154 threaded upon the stud serving to hold the beater 148 in place relatively to the beater 146. The beater 148 is normally held in closed position relatively to 90 the beater 146 by means of a coiled spring 156 having one end engaged in a recess in the beater 146 and its other end engaged in a recess in an arm 158 formed on the beater 148. When the beater 148 is in closed position relatively to the beater 146, the forward portions of the lower or work-engaging surfaces of the beaters form a substantially unrecessed face for engagement with the welt. The beater 148, however, when in 95 closed position, lies in the path of the welt slashing knife, and mechanism is provided for swinging said beater about its pivot stud 150 out of the path of the slashing knife as the knife executes its welt slashing stroke. 100 To this end an arm 160 is secured to the forward end of a rock shaft 162 mounted in a bearing in the bracket 73 secured to the hammer lever. The arm 160 is formed with a forwardly extending projection 164 arranged to engage the projection 166 on the rear end of the beater 148. During the advancing stroke of the knife the projection 164 on the arm 160 engages the projection 166 on the beater 148 and swings the beater 110 115 outwardly about its pivot stud 150 out of the path of the knife. The necessary movement is imparted to the arm 160 to thus actuate the beater 148 by the lever 70 which is formed with a lateral extension 168, arranged to engage the upper side of the projection 170 on the arm 160, as shown in Fig. 4. Through the mechanism described the movement of the lever 70 which imparts a 120 slashing stroke to the knife during the downward movement of the forward end of the hammer lever also moves the beater 148 out of the path of the knife. The pivotal movement of the beater 148 outwardly relatively to the beater 146 is limited by the en- 125 130

gagement of a pin 157 secured in the stud 150 with one end of a slot 159 cut in the upper end of the projection 152.

Having explained the nature and object 5 of the invention and having specifically described a machine embodying the various features thereof in their preferred forms, what is claimed is:

1. A welt beating machine, having in 10 combination, a welt support, welt beating means, welt slashing means, and mechanism acting automatically after the welt slashing means is thrown into operation to cause the same to cut at least a predetermined number of slashes in the welt before it is thrown 15 out of operation.

2. A welt beating machine, having in combination a welt support, welt beating means, welt slashing means, and mechanism 20 for throwing the welt slashing means into operation to slash the welt and for throwing the welt slashing means out of operation automatically after a predetermined number 25 of slashes have been cut in the welt.

3. A welt beating machine, having in combination, a welt support, welt beating means, welt slashing means normally out of operation, mechanism under control of the operator for throwing the welt slashing 30 means into operation, and automatically acting mechanism for causing the welt slashing means to cut at least a predetermined number of slashes in the welt, and for then throwing the welt slashing means 35 out of operation.

4. A welt beating machine, having in combination, a welt support, welt beating means, welt slashing means normally out of operation, mechanism under control of the 40 operator for throwing the welt slashing means into operation, and mechanism for throwing the welt slashing means out of operation automatically after a predetermined number of slashes have been cut in the welt.

5. A welt beating machine, having in combination, a welt support, a welt beater, welt slashing means, mechanism for actuating the welt slashing means to cause the same to cut slashes in the welt at regular intervals during which the beater delivers a 50 predetermined number of blows on the welt, and means for throwing said actuating mechanism into operation and for throwing the same out of operation automatically 55 after a predetermined number of slashes have been cut in the welt.

6. A welt beating machine, having in combination, a welt support, welt beating means, and a reciprocatingly pivoted welt 60 slashing knife having its edge extending transversely to its plane of movement, and means for swinging the knife to slash the welt.

7. A welt beating machine, having in 65 combination, a welt support, welt beating

means, and a reciprocating welt slashing knife pivoted to swing during its operative movement on an axis transverse to the direction of feed of the welt.

8. A welt beating machine, having in 70 combination, a welt support, welt beating means, and a reciprocating welt slashing knife having an operative movement in a direction transverse to the plane of the welt.

9. A welt beating machine, having in 75 combination, a welt support, a welt beating hammer, a hammer lever, a welt slashing knife, and means for actuating the knife from the hammer lever.

10. A welt beating machine, having in 80 combination, a welt support, a welt beating hammer, a hammer lever, a welt slashing knife pivoted to swing upon an axis transverse to the direction of feed of the welt, and means for actuating the knife from the 85 hammer lever.

11. A welt beating machine, having in combination, a welt support, welt beating means, a reciprocating welt slashing knife, and means whereby the knife may be angularly adjusted. 90

12. A welt beating machine, having in combination, a welt support, welt beating means, a welt slashing knife, and means whereby the knife may be adjusted laterally. 95

13. A welt beating machine, having in combination, a welt support, welt beating means, a welt slashing knife, and means whereby the knife may be adjusted angularly to adjust the angle of the slashes made 100 by the knife in two different planes.

14. A welt beating machine, having in combination, a welt support, welt beating means, a welt slashing knife, and means 105 whereby the knife may be adjusted angularly in two different planes and laterally.

15. A welt beating machine, having in combination, a welt support, a welt slashing knife, having an operative movement in an arcuate path, a beater normally engaging the welt at a point in the path of the knife, and means for mounting the beater to permit the same to be moved out of the path of the knife. 110

16. A welt beating machine, having in combination, a welt support, a welt slashing knife, a welt beating hammer normally engaging the welt at a point in the path of the knife, a hammer lever, and means for moving the hammer out of the path of the knife 120 from the hammer lever.

17. A welt beating machine, having, in combination, a welt support, welt beating means, and a reciprocating welt slashing knife having an operative movement in a direction transverse to the plane of the welt and in a plane substantially perpendicular to the plane of the welt and parallel with the normal direction of feed. 125

18. A welt beating machine having, in combination, a welt support, welt beating means, and a reciprocating welt slashing knife arranged to cut transverse slashes in the welt oblique to the plane thereof, and having an operative movement in a direction transverse to the plane of the welt.

19. A welt beating machine having, in combination, a welt support, welt beating means, a welt slashing knife and mechanism for actuating the knife to cause the same to cut slashes in the welt at regular intervals during which the beating means delivers a predetermined number of blows on the welt comprising a cam wheel, means for rotating the cam wheel in timed relation to the beating means, and a device actuated at regular intervals by the cam wheel and acting when actuated by said wheel to throw the welt slashing knife into operation.

20. A welt beating machine having, in combination, a welt support, a welt beater, a welt slashing knife, mechanism for actuating the knife to cause the same to cut slashes in the welt at regular intervals during which the beater delivers a predetermined number of blows on the welt, comprising a cam wheel, means for rotating the cam wheel in timed relation to the beater, and a device actuated by the cam wheel at regular intervals to throw the slashing knife into operation.

mined number of blows on the welt, comprising a cam wheel, means for rotating the cam wheel in timed relation to the beating means, a device actuated by the cam wheel 30 at regular intervals and acting when actuated thereby to throw the welt slashing knife into operation, means under control of the operator for throwing the rotating means into operation, and mechanism 35 acting automatically to throw the rotating means out of operation when the cam wheel has described a predetermined rotary movement.

21. A welt beating machine having, in combination, a welt support, a welt beating hammer, a hammer lever, a welt slashing knife, a movable carrier therefor, a knife actuating lever pivoted on the hammer lever, an abutment for engaging the 45 knife actuating lever to cause the same to swing during the movements of the hammer lever to actuate the knife, and means for moving the abutment into and out of operative position with relation to the knife 50 actuating lever.
